UNITED STATES PATENT OFFICE.

RAY S. WILBUR, OF LYNDHURST, NEW JERSEY, ASSIGNEE TO WESTERN ELECTRIC COMPANY, INCORPORATED, OF NEW YORK, N. Y., A CORPORATION OF NEW YORK.

TESTING SYSTEM.

1,396,800.

Specification of Letters Patent. Patented Nov. 15, 1921.

Application filed December 28, 1918. Serial No. 268,744.

To all whom it may concern:

Be it known that I, RAY S. WILBUR, a citizen of the United States, residing at Lyndhurst, in the county of Bergen, State 5 of New Jersey, have invented certain new and useful Improvements in Testing Systems, of which the following is a full, clear, concise, and exact description.

This invention relates to electrical testing 10 systems and more particularly to systems for testing and adjusting apparatus used in signaling over telephone line circuits.

In connection with some telephone lines it 15 is desirable to employ signaling currents of one character suitable for transmission over the line from a distant station and to provide at the receiving station a relay or other means responsive thereto for translating such current into current suitable for operating the signaling apparatus at the receiving station.

Inasmuch as the translating means must 20 be responsive to incoming current of the proper character irrespective of normal variations in the electrical characteristics of the associated line, it is desirable to provide means for quickly and readily testing the operation of such translating means in order that any necessary adjustment may be 25 made to insure its response under any usual operating conditions.

It is the object of this invention to provide 30 an improved system for testing the operation of such translating means.

To attain this object, in accordance with 35 a feature of the invention, switching means is provided so that such relays may be removed from their associated line circuits and subjected to electrical conditions simulating those under which the relay should 40 respond, the operation of such relay in response thereto being indicated by suitable signaling means.

This and other objects not specifically 45 mentioned above will more clearly appear from the following specification and the annexed drawing in which the figure shows diagrammatically one embodiment of the invention.

In the accompanying drawing, a relay 3 50 in series with a condenser 4 is normally connected to the line conductors 1 and 2, through the normally closed tip and ring contacts, respectively, of a control jack 5.

The grounded normal contact of such relay

is also normally connected to the winding of a relay 6 through a local contact of jack 5, thereby maintaining relay 6 in an operated condition. The line conductors 1 and 2 are also normally continued to the winding of a drop 7, and suitable means such as the usual jack may be associated with the drop 7 to permit connection to be made with the line circuit. A relay 9, controlled by relay 6, is provided for interrupting the continuity of the line conductors and connecting a source of signaling current to the portions of such line conductors which lead to the drop 7. Resistances 10 to 15, inclusive, are associated with the tip and ring contacts of plug 16 to form an artificial line circuit which may be varied by the shunting of resistance 12 upon the actuation of key 17. A source of signaling current 19, corresponding in character to that at the distant station of the line, is provided and may be connected to the artificial line upon the actuation of either of keys 17 and 18. A relay 21, similar to relay 6, is associated with the sleeve contact of plug 16 to replace the latter mentioned relay upon the engagement of the plug with the jack 5. A signaling lamp 20 is controlled by relays 21 and 22 and keys 17 and 18 to indicate the operation of relay 3 under the testing conditions.

It is thought that the invention may be more fully comprehended from the following description of operation of the embodiment shown.

Upon the receipt of an incoming call, signaling current similar to that produced by the source of current 19 flows over the line conductor 2 from the distant station, through the normally closed ring contact of control jack 5, condenser 4, the winding of relay 3, the normally closed tip contact of jack 5, the line conductor 1, and returns to the distant station. Relay 3 operates and, by opening its normal contact, releases normally operated relay 6, thereby completing the circuit and causing the operation of relay 9. The opening of the normal contacts of relay 9 removes the conductors leading to the drop 7 from their normal association with the line conductors 1 and 2, and the closure of the alternate contacts of such relay causes the operation of the drop over a circuit established from the source of signaling current 23, through the right-hand alternate contact of relay 9, the winding of drop 7, and

the left-hand alternate contact of relay 9 to ground.

When it is desired to test the operation of relay 3, plug 16 is inserted into the control jack 5, whereupon by the opening of the normally closed tip and ring contacts of jack 5, the relay 3 and the condenser 4 are removed from their association with line conductors 1 and 2 and the drop 7, and are bridged across the artificial line circuit including resistances 10 to 15, inclusive, associated with the tip and ring contacts of plug 16. By the opening of the normal local contact of jack 5, relay 6 is removed from association with the contact of relay 3 and is maintained in an operated condition by the simultaneous closure of the alternate local contact of jack 5. However, relay 21 replaces relay 6 in its association with relay 3 and is operated over a circuit established from battery, through the winding of relay 21, the sleeve contacts of plug 16 and jack 5, and the contact of relay 3 to ground. The testing operator actuates key 18, thereby establishing a circuit from source of current 19, through the middle contact of key 18, resistances 15 and 14, ring contacts of plug 16 and jack 5, condenser 4, the winding of relay 3, the tip contacts of jack 5 and plug 16, the resistances 10 and 11, and the upper contact of key 18 to ground. The artificial line including the circuit just traced and the bridge thereacross, consisting of resistances 12 and 13, represents one condition of the line circuit under which relay 3 should respond. If, therefore, such relay is correctly adjusted it will operate, and by the opening of its normal contact will release relay 21. Thereupon lamp 20 lights and relay 22 is operated over a circuit established from battery, through the lower contact of key 18, lamp 20 and relay 22 in parallel and the contact of relay 21 to ground. Relay 22 in operating, establishes a circuit from battery, through the contact of relay 22 the winding of relay 22 and lamp 20 in parallel, and the contact of relay 21 to ground. Therefore, relay 22 is locked and lamp 20 is maintained in a lighted condition, under the direct control of relay 21 independently of the position of key 18. Thus, if relay 3 does not release upon the release of key 18, the continuation of the lighted condition of lamp 20 indicates the improper adjustment of the contact of relay 3.

After relay 3 has been adjusted to properly respond under the control of key 18, the key 17 is actuated, thereupon completing a circuit from the source of current 19, through the lower middle contact of key 17, resistances 15 and 14, the ring contacts of plug 16 and jack 5, condenser 4, the winding of relay 3, the tip contacts of jack 5 and plug 16, resistances 10 and 11, and the up-

per contact of key 17 to ground. It will be noted that the closure of the upper middle contact of key 17 short-circuits resistance 12, thereby eliminating such resistance from the bridge across the artificial line. Relay 3 should also operate when associated with the modified artificial line including the circuit traced and the bridge thereacross, consisting of resistance 13, since such artificial line simulates another set of electrical characteristics of the line circuit which may be encountered in the normal operation of the telephone system. The closure of the lower contact of key 17 serves to complete a circuit for lamp 20 and relay 22, which is similar to that previously described in connection with the actuation of key 18, and the lamp 20 will be lighted in a similar manner if the relay being tested is properly adjusted.

Relay 3, when adjusted to operate and release properly in connection with both of the two artificial lines, should function in a proper manner under the usual operating conditions of the line circuit, since the artificial lines are so proportioned that they represent the extremes of the conditions which may be encountered. When such adjustment has been made, the removal of plug 16 from jack 5 restores relay 3, condenser 4 and relay 6 to their normal association with the line circuit.

It will be evident from the foregoing description that by means of this invention the translating relay of the line circuit may be readily tested under conditions simulating those encountered in the normal operation of the telephone system, definite indications being given relative to whether it is properly adjusted to respond under such conditions.

What is claimed is:

1. A testing system, comprising electro-responsive means to be tested, a circuit controlled thereby, means for simulating the normal operating condition of such electro-responsive means, switching means for subjecting the electroresponsive means thereto, additional switching means for substituting another circuit for the first mentioned circuit and for maintaining the first mentioned circuit normal, and signaling means controlled by the last mentioned circuit to indicate the operation of the electroresponsive means.

2. A testing system comprising a relay to be tested, said relay being normally associated with a line circuit and maintaining a second relay in an operated condition, artificial lines simulating conditions of the line circuit, switching means for removing the first mentioned relay from the line circuit and for selectively associating it with an artificial line, additional switching means co-operating therewith for substituting a

third relay for the second relay and for maintaining the second relay in an operated condition independently of the first relay, further switching means for applying current to the selected artificial line to operate the first relay and thereby release the third relay, signaling means for indicating the release of the third relay, and a fourth relay also controlled by the release of the third relay to continue the indication when the third relay fails to reoperate upon the removal of the current from the artificial line.

3. A testing system comprising an electro-responsive means to be tested, a normally operated controlling device controlled thereby, means for simulating a normal operating condition of said electroresponsive means, switching means for subjecting said electroresponsive means thereto, a second signal-controlling device, additional switching means for substituting said second signal-controlling device for said first-mentioned signal-controlling device, and for maintaining said first-mentioned signal controlling device operated independently of the electro-responsive device, and signaling means controlled by said second signal-controlling de-

vice to indicate the operation of said electroresponsive means.

4. A testing system comprising a relay to be tested, said relay being normally associated with a line circuit and responsive to the application to the line circuit of current of predetermined character for releasing a normally operated signal-control relay, an artificial line simulating a condition of said line circuit, switching means for disassociating said first-mentioned relay from said line circuit and for associating said relay with said artificial line, said means also maintaining said second-mentioned relay energized independently of said first-mentioned relay, means for impressing current of said predetermined character upon the artificial line, and a signaling device associated with said first-mentioned relay by said switching means to indicate the operation of said first mentioned relay in response to the current of the pre-determined character.

In witness whereof, I hereunto subscribe my name this 27th day of December A. D., 1918.

RAY S. WILBUR.
